ELECTRIC STOP MOTION FOR LOOMS

Ian Stephen Porter, Barnsley, England

Application June 26, 1950, Serial No. 170,453
In Great Britain July 1, 1949

3 Claims. (Cl. 139—336)

1

This invention relates to electric stop motions of looms for weaving and particularly to improvements in the stop motions of looms driven by an independent electric motor provided with an electro-magnetic brake.

The object of the invention is to ensure that the loom will stop at a predetermined point in the cycle of the weaving operation, e. g. when the shuttle is in the shuttle box at whatever point in the cycle the breakage or failure of warp or weft may occur causing the stop motion to operate.

According to the invention the circuit causing the opening of the circuit to the electric motor and the application of the brake is provided with two breaks, the first of which is closed by a relay when the stop motion or any of the stop motions, in case of a loom having more than one stop motion, comes into operation and the second of which is closed by a cam which is timed to come into operation at any desired point in the revolution of the crank cam shaft of the loom.

Thus when the relay is operated by the operation of a stop motion the first break will be closed but the second break will not be closed by the cam until the crank shaft has reached the desired point in the weaving cycle.

Although the invention is not limited thereto it is particularly applicable to either a single or double warp pile carpet loom having a warp stop motion, a heald frame stop motion and a knife band stop motion, and the accompanying drawings, in relation to which the invention will be described, show this application of the invention.

In these drawings:

Fig. 1 is an electrical circuit diagram showing the control of the driving motor and brake from the three stop motions;

Fig. 2 is a front elevation of a construction of a heald frame suitable for controlling the heald frame stop motion;

Fig. 3 is an end elevation thereof;

Fig. 4 is a section on line 4—4 of Fig. 2;

Fig. 5 is an elevation of a form of knife band stop motion, and

Fig. 6 is a section on line 5 Fig. 5.

The circuit shown in the left hand side of Fig. 1 is a normal circuit to a reversing motor having an electromagnetic brake which comes into action to stop the motor immediately the circuit to the motor is broken. In this circuit A, B, and C, represent the three phase leads to the motor and B¹ and C¹ the leads to the electro-magnetic brake. D¹ and D² represent the forward contactor and the reverse contactor respectively and d¹ and d² the switches controlling the forward and

2

reverse movements of the motor, these switches being operated by a starting handle D³. The circuit from the contactors D¹ and D² to the motor contains a thermal overload device D which on coming into operation opens a trip switch d. Emergency push button operated switches E are also arranged at suitable positions in the circuit.

According to the invention the circuit contains a switch f which is normally closed but is opened by an electro-magnet F when a relay circuit to the latter from a transformer T is energised, the energising of this relay circuit being controlled by one of the stop motion devices which it is desired should stop the loom.

As previously stated three stop motion devices are shown in Fig. 1, i. e. a warp stop motion device r², a heald frame stop motion device g² and a knife band stop motion device k².

The stop motion devices r², g² and k² are arranged in parallel and are connected through normally closed contacts r¹, g¹ and k¹ to relays r, g and k respectively so that when one of the devices r², g² or k² operates the corresponding relay r, g or k which closes the contacts r³, g³ or k³ and consequently the relay circuit to the electro-magnet F is closed provided the switch h in the circuit is closed.

The switch h is closed by a cam H operated from the crank shaft of the loom so that the relay circuit to the electro-magnet F is only closed when the cam shaft has reached the desired point in the weaving cycle when it is desired that the loom should be stopped. This point is usually when the shuttle is in the shuttle box but the loom can be stopped at any other point in the weaving cycle by arranging the cam H to close the switch h at such point.

The contacts r¹, g¹ or k¹ can be opened manually if it is desired to put out of operation the corresponding stop motion device r², g² or k².

A tell tale lamp R, G, or K is arranged in parallel with the circuit from the contacts r³, g³ and k³ to the electro-magnet F and these lamps may be arranged on a panel P carrying the relays r, g and k and contacts r³, g³ and k³ or they may be arranged on any desired position on the loom.

In order that the heald frame stop motion device g² can only operate at a predetermined time in the weaving cycle e. g. when a heald is in or approaching its bottom position, a switch g⁴ controlled by a cam H¹ is arranged between the device g² and the relay g so that the device g² will not close the circuit to the relay g until the cam H¹ has closed the switch g⁴.

The cam H¹ is operated from the crank shaft of the loom.

It is to be understood that any other stop motion devices e. g. a weft stop motion may be introduced into the relay circuit in parallel with the stop motion devices r , g and k and that such additional device or devices would control the relay circuit in a similar manner to the devices r , g and k .

The warp stop motion controlling the device r^2 can be of the conventional electrode bar type which is well known.

A knife stop motion for controlling the device k^2 is illustrated in Figs. 5 and 6. In this arrangement the knife severing the pile is traversed backwards and forwards by a cord, catgut or the like hereinafter referred to as the band 1 and the object of the arrangement is to stop the loom not only if the band breaks but if it becomes too slack. To achieve this object the support 2 on which is mounted one of the pulleys 3 over which the band 1 passes is carried on a rod 4 slidably mounted in the bracket 5. A spring 6 located between one end of the bracket 5 and a block 7 on the rod 4 tends to move the latter in the opposite direction to the tension of the knife band 1 on the pulley 3. The block 7 is adjustable on the rod 4 for adjustment of the pressure of the spring 6. A face 8 of the block 7 forms one contact member of the stop device k^2 (Fig. 1) and the other contact member is formed by a contact 9 carried by but insulated from the bracket 5.

The contact members 8 and 9 will be closed should the band 1 break or should it become sufficiently slack that its tension on the pulley 3 is insufficient to prevent the spring 6 from closing the contacts 8 and 9.

A heald frame stop motion suitable for controlling the stop motion device g^2 of the relay is shown in Figs. 2, 3 and 4.

In this arrangement two electrode or contact bars 10 are mounted between the side members 11 of the heald frame near the top thereof and are insulated therefrom. Each bar 10 is connected to an electrical contact 12 by a spring loaded contact plunger 13, each contact plunger being slidably mounted in a block 14 of compressed fibre or other insulating material secured to one of the side members 11 of the frame. The contact 12 is connected by a strip 15 of copper or other material of good conductivity to a terminal 16 and this terminal is connected to an element 18 in the relay circuit by a light spring 17, the element 18 being mounted on an insulator 19 secured to the frame of the loom.

The heald wires 20 which may be flat steel type or of wire type with flattened ends, are slotted at 21 near their upper ends and the electrode or contact bars 10 pass through the slots 21.

The electrical circuit to the element 18 is only complete as the heald frame is approaching its bottom position, the circuit being completed by a "make and break" device such as the switch g^4 and cam H^1 shown in Fig. 1 timed with the movement of the heald frame. Normally when the heald frame approaches the bottom position the tension of the yarn passing through the eye 20a of each heald wire 20 keeps the top of the slot 21 in the wire clear of the electrode or contact bar 10. If however a yarn is broken the corresponding wire 20 falls and the top of the

slot makes contact with the electrode or contact bar 10 thereby completing the relay circuit as the frame approaches its bottom position.

I claim:

5. 1. In an electric stop motion for a warp pile carpet loom driven by an independent electric motor and having an electromagnetic brake, the combination of a warp stop motion, a heald frame stop motion and a knife band stop motion, a circuit for the motor and the brake, a switch in the motor circuit which is normally closed, a solenoid operative when energized to open said switch, a second circuit containing said solenoid and operative when the second circuit is completed to energize the solenoid and open said switch in the motor circuit, a break in the second circuit which is normally open, relays responsive to the operation of the respective stop motions for closing the second circuit when a fault occurs, and a second break in the second circuit which is opened and closed intermittently, the closing of said second break being timed to take place at a desired point in the weaving cycle.
10. 2. An electric stop motion for a loom as defined in claim 1, including a heald frame comprising side members and heald wires having slots near their upper ends and eyes for the passage of yarn therethrough, and wherein said heald frame stop motion consists of two contact bars carried by the side members of the heald frame, each bar having a spring-loaded plunger and a light spring connecting it to said second circuit, said contact bars passing through the slots of the heald wires, and each heald wire being held out of contact with the respective contact bar by the yarn passing through the eye of the wire but permitting the wire to fall consequent upon breakage of the yarn to cause the heald wire to
15. 30. 40. 45. 50. 55. make contact with the respective contact bar to close the second circuit, and including means timed to keep the second circuit open except when the heald frame is approaching its bottom position
3. An electric stop motion for a loom as defined in claim 1, wherein said knife band stop motion comprises a knife band, a pulley around which the knife band passes, a support carrying said pulley and a pair of cooperative contacts in said second circuit with the respective relay, and a spring which loads said support to a predetermined tension and which is operative, when the tension of the band on the pulley falls below the tension applied to the support, to move said support to close said contacts and cause operation of said relay.
